UNITED STATES PATENT OFFICE

IRVING COWLES, OF CHICAGO, ILLINOIS, ASSIGNOR TO UNION BANK OF CHICAGO, OF CHICAGO, ILLINOIS, A CORPORATION OF ILLINOIS, AS TRUSTEE

GAS-HEATED DEVICE

Original application filed July 13, 1925, Serial No. 43,114. Divided and this application filed February 20, 1928. Serial No. 255,520.

This invention relates to improvements in gas heated devices, and more particularly to such devices as soldering irons which are subject to sudden changes from one position to another and, by reason thereof, have, in all instances known to me, heretofore become extinguished because of the low pressure of the gas and the changing positions of the gas supply hose for feeding the burner of the device, the present invention relating to that type of device wherein the gas from service mains constitutes the medium for drawing in atmospheric air for admixture with the gas to produce a blue flame as distinguished from that type wherein compressed air constituted the medium for drawing in gas for admixture for the same purpose, a feature of the device of this invention being that it is adjustable for gas and air supply such as last described or for other premixed gas and air supply.

The main objects of the invention, in harmony with the foregoing, are to provide a device of this character which is continuously and reliably operative with ordinary fuel and illuminating gases, such as are supplied from city mains, to produce a steady blue flame which will not extinguish by sudden changes in positions of the device and wherein the impingement of said flame on the heating surface of the soldering tip or other element to be heated will be substantially the same in all positions of the device and under the usual low pressure conditions common to gas service mains of municipalities.

Further objects of the invention reside in providing a device of this character the burner of which is easily adjustable to adapt the same for use with gases of varying quality measured in B. t. u.'s and to adapt the same for use with premixed gas and air.

Other objects of the invention will be fully understood from the following specification.

In the accompanying drawings illustrating a suitable embodiment of the invention:

Fig. 1 is a side elevation of a soldering iron constructed in accordance with the invention.

Fig. 2 is a fragmentary central longitudinal section of the same on the line 2—2 of Fig. 1.

Fig. 3 is a fragmentary detail view in ele-

vation, partly in section, of the lower end portion of the device.

Figs. 4 and 5 are transverse sections on the lines 4—4 and 5—5, respectively, of Fig. 2.

Figs. 6 and 7 are respective views of a valve and a valve-operating member, respectively, of the device.

Figs. 8 and 9 are fragmentary longitudinal sections of the gas-burner portion of the device illustrating different types of burner tips employed.

Fig. 10 is a transverse section on the line 10—10 of Fig. 1.

The subject matter of the present application is in the nature of a division of my pending application, Serial No. 43,114, filed July 13, 1925, except in so far as slight changes in structure from those originally illustrated and described are herein incorporated without, however, departing from the scope and meaning of the claims of said earlier application which were deleted therefrom in response to requirement for division thereof.

The device of the present invention consists of what may be termed a burner head 1 which consists of a cylindrical member having a central passage therethrough which is varied in diameter, the same presenting the portion 2 of least diameter, an intermediate threaded portion 3 of larger diameter, and a threaded discharge end portion 4 of greatest diameter. The gas supply tube 5 is threaded into the outer end portion 2 of said bore, and a gas discharge nozzle 6 is threaded into the intermediate portion 3 thereof. Said nozzle 6 includes the tapered end portion 7 having the central discharge opening 8 and presenting, internally, the tapered valve seat 9 upon which the tapered end of the valve 10 is adapted to seat. The intake end of said nozzle 6 presents a cylindrical bore 11 which corresponds in diameter with the portion 2 and constitutes a continuation of the latter. The body of the valve 10 is cylindrical and snugly fits the bore portions 2 and 11 and is reciprocable therein. Adjacent its outer end the valve 10 is provided with a lateral slot 12 in which the crank-pin 13 of the shaft 14 engages, said shaft 14 being rotatably mounted in a lateral or radial opening in the mem-

55

100

ber 1 which is of larger diameter at its outer than at its inner end and presents the annular shoulder 15 between its ends upon which the annular flange 16 of the shaft 14 bears. The outer end portion of the said radial opening is threaded to receive a packing nut 17 between which and the flange 16 a suitable packing 18 is compressed to produce a gas-tight joint. This portion of the head 1 will be hereinafter referred to as the stuffing box. The shaft 14 is preferably provided with a slot 19 in its outer end for the engagement of a screw driver, the nut 17 being similarly slotted.

15 The position of the valve 10 with respect to the seat 9 is such that when the shaft 14 is turned through an arc of slightly less than one hundred eighty degrees from the position shown in Fig. 2, said valve will be firmly seated.

20 The valve 10 is hollow and is provided with a central discharge port 20 which is of smaller diameter than the opening or port 8 and is axially aligned with the latter. Additional radial ports 21 in the valve 10 connect the interior thereof with the annular recess 22 at or adjacent the upper or base portion of its tapered end so that when said valve is unseated a larger volume of gas will be delivered to the opening 8.

25 In the bore portion 4 of the block 1 there is mounted a threaded member 23 having a tapered inner surface 24 opposed to the external tapered outer surface of the nozzle 6 upon which it is adapted to seat when said member 23 is adjusted to one limit of its movement relatively to the member 1. This tapered surface 24 diverges from the discharge port 25 which extends through the boss or nipple 26 integral with the member 23. The outer end portion of said port 25 is enlarged and threaded to receive the spout element 27, the bore of which is of slightly less diameter than the port 25 and which is adjustable to lengthen the discharge passage, which extends through said spout element or to shorten said passage by entirely removing element 27.

30 The head 1 is provided adjacent its intake end with an annular groove 28. Between the inner annular wall of the latter and the bore portion 2, and extending parallel with the axis of the latter, is a series of air passages 29 which lead from the annular shoulder 30 at the inner end of the bore portion 4 to the outer end of the head 1. These passages 29 are spaced equidistantly from each other and are equally spaced radially from the axis of said head and its central bore. 35 Air is drawn through said openings by the injector-like action of the gas discharged from the opening 8 in the event that the member 23 is disposed with its tapered surface 24 spaced from the outer tapered surface of the nozzle 6 and will be admixed with said gas within

the chamber formed between said tapered surface 24 and the shoulder 30, said chamber being hereinafter termed the "mixing" chamber. Adjustment of the member 23 relatively to the nozzle 6 determines the area of the 70 annular space between the surface 24 and the opposed surface of the nozzle 6 relatively to the aggregate area of the passages 29 to thereby control and determine the proportions of air and gas admixed in said mixing chamber. For this reason I term the latter an "adjustable mixing chamber."

75 A second set of air passages 31 leads from the groove 28 to the other or discharge end of said head 1. These passages are of larger 80 diameter than the passages 29 but are similarly arranged and serve to admit air to the tube 32 when the latter is attached to said head 1, said tube 32 coating with the head 1 and the element 33 to be heated, to 85 form a combustion chamber. It will be noted that the passages 31 constitute the only air intake passages for said combustion chamber, the products of combustion being discharged through the draft openings 33^a and 34 adjacent the element 32. It will also be noted that all passages for gas and air are axially parallel.

90 The gas supply tube 5 is preferably connected with a gas service outlet by means of a flexible hose and in order to obviate twisting of the latter the same is detachably associated with the tube 5 by means of the swivel connection shown in Fig. 2.

95 It will be noted that the outer end of tube 5 is threaded into the inner end or head 35 of a tube 36 of larger diameter than tube 5, a threaded head 37 serving as a closure for the outer end of said tube 36. In said head 37 is a central opening through which the swivel tube 38 projects. The latter is provided adjacent its other end with an annular groove in which the split collar 39 seats. Slidable on said tube 38 are two ring members 40 between which suitable packing 41 is mounted and compressed under the influence of the compression 42 to provide a gas-tight joint between the tubes 38 and 36 while permitting their relative rotation.

100 Slidable on the tube 5 is a collar 43 which is provided with an annular flange 44 carrying projections 45 for engaging the outer surface or end of the head 1 to space said collar 43 and its flange from said head to thus admit lateral flow of air to the air passages 29. A 105 tubular handle 46 of wood or other suitable material is clamped between said flange 44 and the opposed flange 47 of the head 37.

110 In use, the device may be easily and quickly adjusted to suit local conditions as to the character and service pressure of the gas. The latter appears to vary from about 475 to more than 1000 B. t. u's so that the volume of air required to be mixed with the gas to produce a blue flame varies consistently 115 120 125 130

with and in ratio to the richness of the gas. Adjustment of the member 23 not only controls the volume of air admitted to the mixing chamber but also varies the length of the latter, this variation in length being of considerable extent from a point at which the full volume of air is admitted to the extreme outer position of said member 23 and is important in the case of richer gases to obtain a more complete and intimate mixture of air and gas as the length of the mixing chamber is increased. If, on the other hand, the available fuel gas is premixed with air as is the case in some factories, the member 23 may be adjusted to entirely shut off the air supply to the mixing chamber.

When the spout element 27 is in the position shown in Fig. 2, the jet of burning gas discharged will be long and thin and will be rendered still thinner by adjusting said member 27 to project farther outwardly. By entirely removing said member 27 the jet will be increased in diameter, the dimensions of said jet being varied by adjustment of the valve 10. Obviously the packing 18 serves also to resist free rotation of the shaft 14 so that it will be retained firmly in any position to which it is adjusted.

Control of the gas supply below the minimum permitted by the valve 10, is effected by means of the valve controlling the service outlet with which the device is connected.

An advantage of the structure appears to lie in the fact that it may be manipulated as desired when in use without affecting the steadiness of the flame jet. The latter is steady when the device is associated with the combustion chamber and element to be heated as well as when disassociated therefrom. This appears to be novel in the art as officials of gas companies have marveled at this steady performance stating that it is the first and only device of this general character which would not extinguish upon a sudden change of position as had been the case with all previous devices brought to their attention. This advantage is believed to result from the arrangement of air passages parallel with the gas duct on the one hand and the provision of a sufficiently large and unobstructed gas outlet port in the valve 10 to permit of a steady flow. But practice has also demonstrated that the draft passages or outlets from the combustion chamber have a strong influence on this characteristic of steady burning in all positions.

It will be noted that the draft outlets 33^a are of a peculiar shape and relative arrangement, and include the perforations 34. In the instance illustrated the element 33 to be heated has flat sides upon one of which it will usually rest when idle, these flat sides being flush with the draft openings 33^a. The recesses 48 of the member 33 coact with the openings 33^a to permit exhaust of products

of combustion and, in use, the flame jet extends into the said recesses 48. In order that this may occur when the device is horizontally disposed, to the end that the maximum heating surface of member 33 may be covered by the flame jet, it is necessary to combat a vertical cross-draft of air which heat at this point will naturally produce. The draft openings 33^a and perforations 34 are so shaped and relatively arranged as to be substantially out of vertical alignment with each other regardless of the position of the flat surfaces of the tip when the device is substantially horizontally disposed thus preventing a direct updraft transversely of and tending to deflect the flame jet. A slight upward deflection of the latter is noticeable but is not sufficient to prevent part of the flame jet to enter the lowest recess 48 of the member 33.

Obviously the temperature of the member 33 will be determined by the area of surface against which the flame jet impinges as compared to the convection surface thereof (assuming the gas to be of a standard quality and pressure) this temperature being, of course, lowered by contact of the member 33 with solder and the metal to be joined which absorb the heat very rapidly proportionately to thickness, etc. Hence, the size, shape and heating surface of the member 33 as well as the volume of fuel used must be changed and varied to adapt the device for so-called light, medium and heavy duty service and for other reasons known to persons skilled in the art.

The tube 32 is, as shown, telescopically engaged with the member 1, the joint between these elements being substantially air tight. It will further be noted that the tube 32 has no air intake openings other than the air passages 31.

In use the head 1 becomes quite hot, the temperature being such that contact of fingers with even the flange 44 will cause burns. The air admitted to the tube 32 and to the mixing chamber is heated to a very appreciable degree in the air passages 31 and 29, respectively, and may, by reason of such pre-heating, present an advantage over cooler air passing more directly into admixture with the gas in the mixing chamber and into contact with the flame jet, respectively, which is reflected in greater operating and heating efficiency, it being seemingly obvious that there can be no greater loss of heat from the flame in this structure by absorption thereof by the member 1 than is true of any Bunsen type burner, the loss in the instant case being at least partly neutralized by the preheating of air as above mentioned.

I claim as my invention:

1. A device of the kind specified including a head having an axial gas-duct therethrough, a mixing chamber between the ends

of said member associated with said duct, air passages parallel with said gas-duct extending from the gas intake end of said head to one end of said mixing chamber, a combustion chamber concentric with said head and having discharge openings for products of combustion in its peripheral wall only at its outer end arranged for direct reception of fluid from the mixing chamber, and air 10 passages parallel with said gas-duct and first-mentioned air passages and arranged outwardly of the latter extending from the intake end of the head to the intake end of the combustion chamber.

15 2. A device of the kind specified including a head provided axially thereof between its ends with a mixing chamber, an axial gas-duct leading from one end of said head into one end of said chamber, a plurality of 20 air ducts parallel with and disposed around said gas-duct leading from the intake end of said head to said end of said chamber, a second set of air ducts parallel with the first-named and arranged around the same extending 25 through said head, a burner member having a discharge duct axially aligned with the gas-duct and adjustably mounted in and constituting a closure for the discharge end of said mixing chamber for varying the length 30 of the latter.

35 3. A device of the kind specified including a cylindrical head having an axially disposed mixing chamber between its ends, an axial gas-duct leading from the intake end of said head to one end of said chamber, a tapered tip at the discharge end of said duct, a plurality of air ducts parallel with said gas-duct, and arranged around the latter, leading from the intake end of said head to the 40 said chamber at the base of and around said tapered tip, a second set of air-ducts parallel with said first-named set, and arranged around the latter, extending through said head, a burner member having a central 45 orifice axially aligned with the gas-duct and having an inner tapered wall converging at the intake end of said orifice, adjustably mounted in the discharge end of said head and constituting an end wall of said chamber, said tapered wall coacting with said 50 tapered tip to control the volume of air admitted to the mixing chamber.

55 4. A device of the kind specified including a cylindrical head having an axially disposed mixing chamber between its ends, an axial gas-duct leading from the intake end of said head to one end of said chamber, a valve seat bordering the discharge end of said gas-duct, a plurality of air ducts parallel with said 60 gas-duct, and arranged around the latter, leading from the intake end of said head to the said chamber rearwardly of said valve seat, a second set of air ducts parallel with said first-named set, and arranged around the latter, extending through said head, a burner

member having a central orifice axially aligned with the gas-duct and having an inner wall formation coacting with said valve seat to control the volume of air passing the latter, said burner member adjustably mounted in the discharge end of said head and constituting a closure for said mixing chamber.

70 5. A device of the kind specified including a gas burner comprising a head having a central gas-duct, a supply pipe connected with one end of said duct, a discharge nozzle at the other end of said duct, a member having a central discharge port mounted between the ends of said duct and presenting a valve seat around said port opposing the intake end of said duct, a hollow valve having a central discharge port at one end and lateral discharge ports between its ends reciprocably mounted in said duct and adapted to seat on said valve seat to thereby shut off flow from said lateral ducts, a laterally disposed valve operating element in said head associated with said valve for moving same toward and from said seat, there being a mixing chamber between said member and said nozzle, and air ducts disposed parallel with and around said gas-duct leading from the intake end of said head to the nearest adjacent end of said mixing chamber.

75 6. A device of the kind specified including a gas burner comprising a head having a central gas-duct, a supply pipe connected with one end of said duct, a discharge nozzle element mounted in the other end of said duct and adjustable longitudinally of the latter, a member having a central discharge port mounted between the ends of said duct and presenting a valve seat around said port opposing the intake end of said duct, a hollow valve having a central discharge port at one end and lateral discharge ports between its ends reciprocably mounted in said duct and adapted to seat on said valve seat to thereby shut off flow from said lateral ducts, a laterally disposed valve operating element in said head associated with said valve for moving same toward and from said seat, there being a mixing chamber between said member and said nozzle, and air ducts disposed parallel with and around said gas-duct leading from the intake end of said head to the nearest adjacent end of said mixing chamber, said mixing chamber being adjustable in length by adjustment of said nozzle element.

of which opposes said nozzle element, a hollow valve having a central discharge port at one end and lateral discharge ports between its ends reciprocably mounted in said duct and adapted to seat on the other of said 5 valve seats to thereby shut off flow from said lateral ducts, a laterally disposed valve operating element in said head associated with said valve for moving same toward and from said seat, there being a mixing chamber between 10 said member and said nozzle, and air ducts disposed parallel with and around said gas-duct leading from the intake end of said head to the nearest adjacent end of said mixing chamber, said nozzle element having a 15 surface adapted to seat on the valve seat of said member opposed thereto to thereby shut off or control the volume of air admitted to the mixing chamber, the latter being adjustable in length by adjustment of said nozzle element.

8. A device of the kind specified including a handle portion consisting of a burner head, a gas feed pipe for one end thereof, a handle mounted on said pipe, a discharge nozzle in 25 the other end of said head axially aligned with said feed pipe, a gas-duct in said head between the feed pipe and the nozzle, said duct being of larger diameter at its discharge end than at its intake end and being provided 30 at substantially the meeting point of said portions of different diameters with a partition wall having a central port bordered at both ends by valve seats on one of which said nozzle is adapted to seat, a valve having a central aperture reciprocably mounted in the 35 intake end portion of said duct and adapted to seat on the other of said valve seats, there being additional gas-ducts in said valve permitting flow of gas past the same when it is 40 moved from its seat, said discharge nozzle being adjustable toward and from said wall and the space between the latter and said nozzle constituting a mixing chamber, and air ducts leading from said mixing chamber to 45 atmosphere, said ducts being disposed parallel with and around the smaller diameter portion of said gas-duct, said nozzle constituting a valve for controlling the volume of air admitted to the mixng chamber through 50 said ducts.

9. A device of the kind specified including a burner member having an axial gas-duct having intake and discharge end portions communicating with each other through an 55 axial port, a manually operable valve mounted in the intake end portion of said duct and coacting with said port to control the flow of gas through the latter, air ducts extending parallel with and arranged around the intake 60 end portion of said duct leading from atmosphere toward the discharge end portion of said duct, and a manually adjustable discharge nozzle mounted in the discharge end of said duct and constituting a means for controlling the said air ducts.

10. A device of the kind specified including a burner member having an axial gas-duct having intake and discharge end portions communicating with each other through an axial port, a manually operable valve mounted in the intake end portion of said duct and coacting with said port to control the flow of gas through the latter, air ducts extending parallel with and arranged around the intake end portion of said duct leading from atmosphere toward the discharge end portion of said duct, an adjustable discharge nozzle constituting a closure for said discharge end of said duct and a means for controlling said air ducts, the space between said nozzle and said port constituting a mixing chamber adjustable in length. 70

11. A device of the kind specified comprising in combination, a cylindrical head having a central gas-duct including a mixing chamber, means for connecting the same with a source of gas under pressure, a cylindrical combustion chamber having air tight association with the discharge end of said head at one end and carrying an element to be heated at 80 its other end, there being openings for the discharge of products of combustion at the last-named end of said chamber, said head being provided adjacent its intake end with an annular groove, there being a series of air ducts leading from said groove to the said combustion chamber and another series of air ducts leading from the intake end of said head to the said mixing chamber, said several series of air-ducts parallel with each other and with said gas-duct. 85

12. A device of the kind specified including a cylindrical head having a central valve-controlled gas-duct, a burner nozzle at one end of said duct, means for connecting the other end of the latter with a source of gas under pressure, there being a mixing chamber between the ends of said head, a cylindrical combustion chamber associated with said head at one end and with an element to be heated at its other end and having discharge openings in the last-named end, said chamber arranged for axial flow of gas therethrough, and two sets of air ducts in said head arranged around and parallel with said gas-duct, both sets communicating at one end with atmosphere, one thereof communicating at its other end with said mixing chamber and the other thereof with said combustion chamber. 100

13. A device of the kind specified including a cylindrical head having a central valve-controlled gas-duct, a burner nozzle at one end of said duct, means for connecting the other end of the latter with a source of gas under pressure, there being a mixing chamber between the ends of said head, a cylindrical combustion chamber associated with said head at one end and with an element to be heated at its other end and having discharge 115

openings in the last-named end, said chamber arranged for axial flow of gas therethrough, there being an annular groove adjacent one end of said head, a set of air ducts through said head extending from the said mixing chamber to the outer end of said head and disposed out of communication with said groove, and a set of air ducts of larger cross-sectional area than the first-named extending from said groove to said combustion chamber, all of said ducts being parallel with each other and with said gas-duct.

14. A device of the kind specified including a burner head having an axial gas-duct, a mixing chamber at the discharge end of said duct, air ducts parallel with and arranged around the gas duct leading into the intake end of the mixing chamber, a burner nozzle mounted in the discharge end of the mixing chamber and adjustable axially of said head for varying the length of said chamber, and means within said chamber coacting with said nozzle for controlling said air passages.

15. A device of the kind specified including a burner head having an axial gas-duct terminating in an axial gas discharge port, a mixing chamber concentric with said duct into which said port discharges, air ducts arranged around and extending parallel with said duct for admitting air to the intake end of said mixing chamber, a burner nozzle adjustably mounted in the discharge end of said chamber for varying the length thereof, and a valve seat bordering said discharge port and coacting with said nozzle to control the flow of air into said mixing chamber.
